CARRYING CASE FOR BUSINESS MACHINES OR THE LIKE

Carl W. Sundberg, Bloomfield Hills, and Montgomery Ferar, Huntington Woods, Mich., assignors to Sperry Rand Corporation, New York, N.Y., a corporation of Delaware

Filed Mar. 5, 1962, Ser. No. 69,083

Term of patent 14 years

(Cl. D87—5)

FIG. 1

FIG. 2

FIG. 1 is a front perspective view of a carrying case for business machines or the like showing our new design; and

FIG. 2 is an inverted rear perspective view thereof.

The design is characterized by a wide central grooved band separating two ridged sidewalls in combination with a plurality of support members as shown.

We claim:

The ornamental design for a carrying case for business machines or the like, as shown and described.
